UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,848, dated October 24, 1893.

Application filed September 19, 1893. Serial No. 485,913. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of connected ornamental scrolls forming a series of panels o with sprays of flowers and leaves arranged in the said panels as represented in the accompanying drawing. The flowers and leaves spring from vase-like ornaments in the center of said panels.

What I claim is—

The design for a wall paper herein shown and described.

Witness my hand this 15th day of September, 1893.

CHARLES BOOZE.
